(57) **CLAIM**

I claim the ornamental appearance of a sawhorse, as shown and described.

DESCRIPTION

FIG. 1 is a top perspective view of a sawhorse, with the broken line showing of a bolt being for illustrative purposes and forming no part of the claimed design;

FIG. 2 is a right side elevational view thereof with the left side being a mirror image, with the broken line showing of a bolt being for illustrative purposes and forming no part of the claimed design;

FIG. 3 is an end elevational view thereof with the opposite end being a mirror image, with the broken line showing of a bolt being for illustrative purposes and forming no part of the claimed design;

FIG. 4 is a top view thereof, with the broken line showing of a bolt being for illustrative purposes and forming no part of the claimed design; and,

FIG. 5 is a bottom view thereof.
